UNITED STATES PATENT OFFICE.

WILLIAM F. FLETCHER AND HUGH N. RICHARDSON, OF DRILL, VIRGINIA.

COMBINATION INVALID BED AND CHAIR.

1,179,907.

Specification of Letters Patent. Patented Apr. 18, 1916.

Application filed February 6, 1915. Serial No. 6,563.

To all whom it may concern:

Be it known that we, WILLIAM F. FLETCHER and HUGH N. RICHARDSON, citizens of the United States, residing at Drill, in the county of Russell and State of Virginia, have invented a new and useful Combination Invalid Bed and Chair; and we do hereby declare the following to be a full, clear, and exact description of the invention, such as will enable others skilled in the art to which it appertains to make and use the same.

This invention relates to an improved invalid bed and chair, and as an object of the invention it is the aim to provide a folding bed chair having an opening in the seat portion provided with a removable closure, whereby the patient or invalid may easily attend to the calls of nature.

20 A further object of the invention is to provide a bed of this nature whereby the patient may lie straight or flat out, and when improving or becoming partially convalescent may be reclined in partial sitting positions, 25 and after having recovered substantially, the bed may be adjusted whereby the invalid or patient may be disposed in a complete sitting position.

In practical fields the details of construction may necessitate alterations, falling within the scope of what is claimed.

The invention comprises further features and combination of parts, as hereinafter set forth, shown in the drawings and claimed.

35 In the drawings:—Figure 1 is a view in side elevation showing the combined bed and chair adjusted for use as an invalid bed. Fig. 2 is a bottom plan view of the bed showing parts broken away. Fig. 3 is a sectional view longitudinally. Fig. 4 is a sectional view showing the foldable back and leg supporting portion of the bed adjusted whereby the device may be used as a chair, and showing the removable closure of said 45 opening lowered.

Referring more particularly to the drawings, 1 designates a supporting frame comprising side parts 2, each of which consists of a longitudinal rod 3 having downwardly 50 extending legs 4. The legs of each side part are connected by the brace plate 5, the ends of which are formed in rolls 6 to receive the legs. The brace plates of the side parts are connected, at one end of the supporting frame by means of the rod 8. Mounted in bearings of the brace plates at the other end

of the frame is a rocking shaft 9 having downwardly extending arms 10, one at each end, and the single upwardly extending arm 11. On one end of the rocking shaft is a lever 12. Bolted to the upper rod of the supporting frame is a bed frame 13 comprising a stationary section 14 (which is bolted to said supporting frame as shown at 15), and the back and leg supporting sections 17 and 18, which are hinged or pivoted at 19 and 20 to the stationary section. These sections are so constructed as to support a combined bed and chair spring 21, which consist of three hinged sections 22, 23 and 24, the 60 section 22 engages the stationary section of the bed frame, whereas the sections 23 and 24 are supported respectively by the back and leg supporting sections. The spring construction of the section 22 is constructed 65 with a suitable opening 25, with which the opening 26 in the mattress 27 registers, that is, when the mattress is placed on the spring. Secured at 29 to the under surface of the bed frame are straps 30 and 31, and mounted 70 in bearings 32 of said strap is a U-shaped member 33, and one of the side rods of this U-shaped member terminates into a crank handle 34. The free end of the U-shaped member has secured to it a closure 35 suitably padded or provided with a cushion 36, and designed to close the openings 25 and 26. By manipulating the crank handle the closure may be lowered, in which case a suitable receptacle may be placed beneath the 75 opening, when the invalid wishes to respond to the calls of nature. Pivoted at 37 to one end of the strap 30 is a lever 38, which may be thrown or disposed under the closure, and when in such position the free portion of the lever engages a hooked end 40 of the strap 31, thereby securely supporting 80 said closure in the openings. Secured to the under face of the leg supporting section is a bracket 43, to the transverse rod 44 of which the links 45 are pivotally connected, 85 as shown at 46. The ends 47 of the links are in turn connected to the arms 10. To the under face of the back supporting section a bracket 48 is secured, to which a link 49 is 90 pivoted, which in turn is pivoted to the arm 11 of the rocking shaft. 95

100 It will be observed that by throwing the lever 12 to the position shown in Fig. 1 the back and leg supporting sections are arranged horizontally. By throwing the lever 105 in the direction of the arrow *a*, and causing

the same to engage any one of the notches 50 of the rack 51 it will be observed that the back and leg supporting section may be inclined correspondingly, so as to support the patient or invalid in a partially sitting position. It will be observed, however, that said back and leg supporting sections may be disposed in order to support the patient in a full sitting position.

10 It will be noted, that when the lever 12 is disposed as shown in Fig. 1 a latch 53 is employed to prevent movement of the lever in the direction of the arrow *a*. When it is desired to operate the lever, the latch may be thrown out of its path. The mattress is provided with a suitable cover 54, which is buttoned at 55 to the mattress. This cover consists of two parts 56 and 57, the part 56 covers the horizontally disposed portion (which is provided with an opening) of the mattress and the back supporting portion of the mattress, while the part 57 covers the leg supporting portion of the mattress. When the patient or invalid wishes to respond to the calls of nature, the part 56 of the cover may be unbuttoned and removed from over the opening.

15 The invention having been set forth, what is claimed as new and useful is:-

20 In an invalid bed, a supporting bed frame comprising upper longitudinal side bars and lower longitudinal side bars, a mattress supporting frame comprising a middle section rigidly fixed to the corresponding ends of the upper side bars of the supporting frame and forming no part thereof, a back section hingedly connected to one end of

the middle section and being disengageably supported normally upon the opposite ends of the upper side bars of the supporting frame, a leg supporting section hingedly connected to the other end of the middle section and adapted to be swung downwardly in engagement with two of the supporting legs of the supporting frame, 45 a rock shaft mounted in the lower side bars of the supporting frame adjacent the end opposite the leg supporting section, said rock shaft having a pair of arms, links connected to said arms and to the leg supporting section, said rock shaft having a third arm extending therefrom in a direction directly opposite the pair of arms, a link connecting the third arm and the back section, a rack on one side of the upper part of the supporting frame, a lever fixed to one end of the rock shaft for rocking the shaft to tilt the back and leg sections upon corresponding inclinations and adapted to engage said rack to hold said sections in such 60 adjusted tilted positions, said lever near where it is connected to the rock shaft having a tooth, and a pawl to engage said tooth when the lever is out of engagement with the rack to hold the leg and back sections 65 aligned with the middle section.

In testimony whereof we have signed our names to this specification in the presence of two subscribing witnesses.

WILLIAM F. FLETCHER.
HUGH N. RICHARDSON.
